ROLL CHUCK ASSEMBLY FOR ROLLING
MILLS OF THE BACKED-UP WORKING
ROLL TYPEHoward H. Talbot, Pittsburgh, Pa., assignor to
United Engineering & Foundry Company,
Pittsburgh, Pa., a corporation of Pennsylvania

Application December 13, 1934, Serial No. 757,310

9 Claims. (Cl. 80—55)

This invention relates to rolling mills of the backed-up working roll type, and more particularly to an improvement in the assembly of mechanism employed to retain the bearing 5 chucks for the rolls of such mills in their operative positions.

The common practice in the construction of mills of this type wherein small working rolls are used, is to mount the bearing chuck for the small 10 working roll within the projected side walls of one of the backing-up roll chucks. The use of this method of mounting chucks in mills in which roller bearings are used, presents a problem of retaining the working roll chucks against axial 15 displacement in such a way that they can be readily removed. The cause for this difficulty is that the working roll chucks are somewhat shorter than the backing roll chucks and, consequently, their outer ends are displaced inwardly from 20 the other ends of the backing roll chucks, rendering the working roll chucks very inaccessible for clamping to prevent axial displacement or for unclamping for the purpose of removal, and as it is necessary to remove the working rolls quite 25 frequently, it is desirable that the disassembling and assembling of the working roll chucks be made as simple and easy as possible. Heretofore releasable clamping plates, or equivalent devices employing a plurality of bolts or screws 30 which have to be removed or released each time the working roll chuck is removed, have been customarily used for this purpose. Due to the inset of the working roll chucks and the consequent difficulty in releasing the screws or bolts 35 of such clamp their use is rendered both awkward and inconvenient as well as undesirable from the standpoint of the time required to disassemble and reassemble them, which it is highly desirable to minimize as much as possible. 40 With this in mind, it is an object of this invention to provide an improved means for releasably holding the working roll chucks of a backed-up mill in place in the backing roll chucks which is extremely simple of construction, de- 45 pendable in operation, and susceptible of being adjusted to permit the removal and assembly of the working roll chucks with a minimum of effort and time.

This and various other objects, as well as the 50 various other novel features and advantages of the invention, will be apparent when the following detailed description is read in conjunction with the accompanying drawings, of which Fig. 1 is an end elevation of a rolling mill incor- 55 porating an embodiment of the invention, and

Fig. 2, a horizontal sectional view taken on the line II—II of Fig. 1 but showing the working roll in plan.

Referring in detail to the drawings, the numeral 1 designates generally a housing of a rolling mill of the 4-high backed-up working roll type in the window 3 of which there is arranged a pair of working rolls 4 and 5 that are laterally supported by a pair of backing rolls 6 and 7. In conformance with the prevailing practice the necks 4a and 5a of the working rolls 4 and 5 are mounted in a pair of bearing chucks 8 and 9 which are in turn nested for vertical and endwise movement in suitable openings 11 and 12 provided therefor in the bottom and top respectively of the bearing chucks 13 and 14 in which the necks 6a and 7a of the backing rolls 6 and 7 are supported. These latter chucks are themselves mounted in the window 3 of the roll housing 1 with the upper one disposed for vertical adjustment under the control of a screw-down mechanism 15.

To prevent any axial displacement of the backing roll chucks 13 and 14 a plurality of releasable end clamps 16 are provided which are held 25 in place by a plurality of suitable bolts 17 threadably engaged in the roll housing 1.

In accordance with this invention to hold the working roll chucks 8 and 9 in place in the backing roll chucks a pair of latches 18 is provided in 30 each backing roll chuck opposite the outer end of each working roll chuck. These latches, as shown, are provided with a substantial face 18a for engaging the working roll chucks and are pivotally supported in the backing roll chucks by 35 pins 19 extended through a pair of spaced brackets 21 and 21a formed on the backing roll chucks, the pins being held in place by collars 19a keyed to the pins between the two brackets 21 and 21a. Between the former of these brackets and the 40 body proper of each chuck a suitable recess 22 is provided to receive and permit the latch associated therewith to be moved completely out of the path of movement of the working roll chucks when disengaged so as to permit the 45 working roll chuck to be freely removed from the backing roll chuck. While, as illustrated in this embodiment of the invention, the latches 18 are disposed to engage the outer end of the working roll chucks in a manner to prevent any out- 50 ward movement thereof in the backing roll chucks and the inward movement prevented by flanges 20 provided on the outer edges of the working roll chucks which seat in offsets 10 in the edges of the backing roll chucks, it will be 55

appreciated that both movements may be prevented by the latches.

To retain the latches 18 in their operative and inoperative positions releasable stops 23 are provided, the stops being so located as to engage the latches on one side when in one position and on the other when in the other position. Such stops may be either simply screw bolts as shown, which must be unscrewed each time the latches are moved, or spring biased depressible spring-type stops which may be simply forced into the face of the backing roll to permit the latches to be moved thereover and automatically returned to their operative positions as soon as the latches are moved past them. In their preferred form the latches are so shaped that the ones on the upper backing roll chuck will fall by gravity into their unlatched position when the stops 23 are moved out of engagement with them. However, to assure and simplify the movement of these latches into and out of their operative and inoperative positions they are keyed or otherwise fastened for rotation on the pins 19 about which they are pivoted and these pins provided with non-circular outer ends projected beyond the face of the housing for the reception of a turning tool by means of which they may be readily turned by an operator from one position to another.

In practicing this invention, as will be readily appreciated by those skilled in the art, the only operations necessary for the removal of the working roll chucks in so far as their retention in the backing roll chucks is concerned, is to remove the latch-engaging stops 23 and turn the latches 18 to their non-engaging positions.

As shown in Fig. 2, it is necessary to provide these latches at one end of the working rolls only as the working roll chucks are so mounted as to prevent their being moved axially on the necks of the working rolls. To accomplish this, an internal shoulder 23a is provided on the inner end of the bearing receiving opening in each of the working roll chucks to engage the inner end of the bearing cage 24 mounted therein, and this cage held against axial movement on the roll neck by a collar 25 mounted on the inner end thereof, and a sleeve 26 mounted on its outer end, the latter being in turn held in place by an assembled retaining ring 27 mounted in a groove 28 provided for its reception adjacent the outer ends of the roll neck.

While such comprises no part of this invention, the backing roll chucks shown are designed to be interchangeable so as to minimize the replacement equipment necessary to maintain a mill in operative condition. This accounts for the chucks at the two ends of the mill as illustrated in Fig. 2 being provided with bracket formations for the reception of working roll chuck-engaging latches, although such latches, for the reasons referred to hereinbefore, are provided at only one end of the rolls.

As will be readily appreciated by those skilled in the art, the working roll chuck retaining latch mechanism provided by this invention greatly facilitates the assembling and disassembling of the working rolls and represents a very desirable improvement over the prior means employed for this purpose.

According to the provisions of the patent statutes, I have explained the principle and mode of operation of my invention and have illustrated and described what I now consider to represent its best embodiment. However, I desire to have

it understood that, within the scope of the appended claims, the invention may be practiced otherwise than as specifically illustrated and described.

I claim:

1. In a rolling mill of the backed-up working roll type a working roll chuck, a backing roll chuck designed to receive said working roll chuck and permit vertical and endwise movement of the latter therein, a releasable latch for engaging and preventing endwise movement of the working roll chuck, said latch being mounted in a recess in said backing roll chuck and means for moving it into and out of engagement with said working roll chuck. 15

2. A roll chuck assembly for use in a rolling mill of the backed-up working roll type comprising a backing roll chuck, a working roll chuck nested in said backing roll chuck, a latch pivotally mounted in a recess in said backing roll 20 chuck adjacent the working roll chuck and movable into and out of engagement with said working roll chuck to prevent relative endwise movement of the working roll chuck in the backing roll chuck. 25

3. A roll chuck assembly for use in a rolling mill of the backed-up working roll type comprising a backing roll chuck, a working roll chuck nested in said backing roll chuck, a latch pivotally mounted in a recess in said backing roll 30 chuck and movable into and out of engagement with said working roll chuck to prevent relative endwise movement of the latter, and releasable means for retaining said latch in its chuck-engaging position. 35

4. A roll chuck assembly for use in a rolling mill of the backed-up working roll type comprising a backing roll chuck, a working roll chuck nested in said backing roll chuck, a pair of latches pivotally mounted in recesses in said backing roll 40 chuck in the sides thereof adjacent said working roll chuck and movable into and out of engagement with said working roll chucks, and means for releasably holding said latches in their operative and inoperative positions. 45

5. A roll chuck assembly for use in a rolling mill of the backed-up working roll type comprising a backing roll chuck, a working roll chuck nested in said backing roll chuck, a latch pivotally mounted in a recess in the side of said 50 backing roll chuck adjacent the working roll chuck and movable into and out of engagement with said working roll chuck, and a pivot pin on which said latch is keyed mounted in said backing roll chuck with its end projecting outwardly therefrom to facilitate the adjustment thereby of said latch. 55

6. In a rolling mill of the backed-up working roll type, a backing roll chuck, a backing roll mounted in said chuck, a working roll, a working 60 roll chuck mounted on the end of said working roll and nested in said backing roll chuck and also held against relative endwise movement on said working roll, and a latch mounted in a recess in the side of said backing roll chuck adjacent 65 the working roll chuck and movable into and out of engagement with said working roll chuck to releasably hold the latter in place in the backing roll chuck. 70

7. In a rolling mill of the backed-up working 70 roll type, a backing roll, a pair of chucks for the opposite ends of said backing roll, a working roll, a pair of working roll chucks mounted on the opposite ends of said working roll and nested in said backing roll chucks, means for prevent- 75

ing relative endwise movement of said working roll chucks on said working roll, and a latch mounted in a recess in the side of one of said backing roll chucks adjacent the working roll 5 chuck nested therein and movable into and out of engagement with said working roll chuck for holding it and the working roll against endwise movement.

8. A roll chuck assembly for use in a rolling mill of the backed-up working roll type comprising a backing roll chuck, a working roll chuck of shorter length than the backing roll chuck nested in the latter at the inner end thereof, and latching means supported in a recess in a 10 side of the backing roll chuck adjacent the working roll chuck and inwardly from the outer end thereof movable into and out of engagement with

the working roll chuck for preventing endwise movement thereof and means for operating said latch from the outer end of the backing roll chuck.

9. A roll chuck assembly for use in a rolling mill of the backed-up working roll type comprising a backing roll chuck, a working roll chuck nested in the backing roll chuck, a latch having a fixed end pivotally supported in said backing roll chuck and a free end provided with an outer 10 face extending at an angle to the axis of the latch which fully engages the working roll chuck when in its latched position and is adapted to be moved in less than 90° to a full unlatched position, and means for releasably retaining said 15 latch in its engaged and disengaged positions.

HOWARD H. TALBOT.
